HUMIDIFICATION UNIT

Paul Campbell Miller, Jr., Milford, Mich., assignor to Skuttle Manufacturing Company, Milford, Mich., a corporation of Michigan

Application November 26, 1954, Serial No. 471,302

4 Claims. (Cl. 312—31.01)

The present invention relates to humidification equipment and more particularly to a display cabinet containing humidifying apparatus for maintaining controlled atmospheric conditions most suitable for cigars or other articles of merchandise which are displayed within said cabinet.

With the advent of self-service stores it has become increasingly important that merchandise be displayed where it is readily accessible to the customers and still be well preserved. This is especially true of merchandise which requires a controlled humidity to assure freshness. One such item which has been seriously affected when displayed in open cabinets is the cigar.

It has been found that cigars, even when well wrapped, may become stale within one day if the surrounding air is relatively dry. When this happens to a cigar it cannot be reclaimed by the merchant merely by placing the cigar in a more humid atmosphere. Hence, it is imperative that the merchant keep his cigars in a cabinet or similar container where the air is properly humidified in order to avoid serious losses.

Various efforts have been made to provide proper humidification for a display cabinet for cigars, but such efforts have proved to be unsuccessful. In most instances the air in the cabinet has not had a uniform humidity. Electric fans have been used for circulating the air in an effort to overcome this shortcoming, but to no avail. Such fans have been found in many instances to increase the humidification problem rather than to solve it.

It is the principal object of the present invention to provide an improved humidification unit which is constructed and arranged so that cigars or other merchandise can be displayed in air having a predetermined uniform humidity while at the same time allowing such merchandise to be readily available to purchasers.

It is another object of the present invention to provide an improved humidification unit of the foregoing character which includes humidifier apparatus which is simple and economical to produce and will assure a uniform humidification of the air surrounding the merchandise within the display cabinet.

It is still another object of the present invention to provide an improved humidification unit of the foregoing character which has a simple and economical alarm system for indicating when there is a shortage of water in the humidifier apparatus.

It is still another object of the present invention to provide an improved humidification unit which includes a cabinet having an open top to provide access to the interior, said cabinet being constructed and arranged to prevent unnecessary circulation of air therein and to include air passages whereby humidified air can flow by convection past the merchandise stored therein thereby assuring a constant and uniform humidification of said merchandise.

It is still another object of the present invention to provide a humidifier unit for use in the cabinet described above, said humidifier unit having an evaporator pan mounted adjacent the aforesaid air passages, the evaporator pan being formed from corrosive resistant materials, such as a polyester resin-fiberglass reinforced mate-

2

rial so that suitable salts can be added to the water therein so that the formation of plant or animal life can be prevented, thereby avoiding disagreeable odors which might have a deleterious effect on such merchandise.

5 Other objects of this invention will appear in the following description and appended claims, reference being had to the accompanying drawings forming a part of this specification wherein like reference characters designate corresponding parts in the several views.

10 In the drawings:

Fig. 1 is a perspective view of an humidification unit embodying the present invention;

Fig. 2 is an enlarged sectional view taken on the line 2—2 of Fig. 1;

15 Fig. 3 is an enlarged fragmentary sectional view showing details of the humidifier apparatus used in the disclosed embodiment; and

Fig. 4 is a schematic wiring diagram of the alarm circuits that may be employed in the present invention.

20 Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

25 Referring now to the drawings, a more detailed description of the invention will be given. The humidification unit 10 includes a cabinet 12 formed of any suitable material having an attractive appearance for display purposes. The illustrated embodiment is formed from sheet metal. It has a base 14, side walls 16 and 18, a front wall 20 and a rear wall 22. Extending over a portion of the interior of the cabinet 12 is a top wall 24. Conventional doors, as seen at 26 and 28, are provided in the front and rear walls. The front wall 20 has its upper portion 30 formed of glass so that the merchandise within the cabinet 12 is more readily visible to prospective purchasers.

30 Extending longitudinally of the cabinet 12 are a plurality of shelves 32, 34 and 36, which if desired may have upturned edges for assisting in retaining in place the displayed merchandise. Positioned adjacent the shelves in spaced relation are longitudinally extending partitions 38, 40 and 42 whose purpose will be described hereinafter. A storage shelf 43 also may be provided within the cabinet 12, if desired.

35 Suspended below the shelves 32, 34 and 36 by metal straps 44 are trays or pans 46, 48 and 50 which are adapted for carrying water for humidification purposes. The pans are spaced from the shelves so that air passages as at 52 and 54 are provided from the surface of the water 56 to regions above the shelves. The pans can be formed from any suitable material, but it is preferred that they be made from polyester resin reinforced with fiberglass for reasons to be explained.

40 Under normal operating conditions the water 56 will evaporate from the pans 46, 48 and 50 and will have to be replenished. In order that this will be done promptly when the level of the water approaches a danger point, an alarm system is provided. Referring to Figures 3 and 4, a description of this system will be given. Since the apparatus associated with each of the pans 46, 48 and 50 is substantially the same, only that used with pan 50 will be described in detail.

45 Positioned adjacent one end of pan 50 is a float or cup 58 preferably formed from a suitable plastic material. The cup 58 has a lug 60 on its lower edge so that when 50 the water in the pan falls below a desired level the lug 60 will contact the bottom of pan 50 and thereafter will

tilt to the position shown in phantom at 62. A small arm or handle 64 projects rearwardly from the upper lip of cup 58 and carried thereon is a mercury switch 66 which is secured in place on the handle 64 by the band 68. Thus, when cup 58 pivots on the lug 60, the mercury switch 66 will tilt closing the electric contacts therein.

One terminal of mercury switch 66 is in series with an electric lamp 68 by conductor 70 and lamp 68 is then connected by conductor 72 to a step down transformer 74. The other terminal of mercury switch 66 is connected to the manually operated switch 76 by conductor 78 and switch 76 is then connected to transformer 74 by conductor 80. Transformer 74 allows low voltages to be used in operating the alarm system which is desirable both from the safety and economy standpoint.

Each of cups 54 and 56 have a similar electric circuit associated therewith for energizing the lamps 82 or 84 in the event water falls below a predetermined level in pans 46 and 48. Such lamps may be located anywhere on the cabinet where they will be readily visible to an attendant. In the embodiment shown in the drawings they are located on a small panel 86 visible from the front of the cabinet 12. Also, included on this panel is the switch 76 for closing the electric circuits to the mercury switches.

In normal operation switch 76 will be closed and water will be in all the pans 46, 48 and 50. Cigars or other merchandise will be positioned on shelves 32, 34 and 36. With the pans full of water the cups 54, 56 and 58 will float thereby holding the mercury switches associated therewith in a horizontal position so that the circuits to each of lamps 82, 84 and 68 will be open. Should the water in any pan fall below a predetermined level the cup in such pan will tilt closing the circuit through its associated lamp. The attendant can then refill such pan thereby assuring proper humidification of the merchandise.

The air movement within the cabinet 12 will result primarily from natural convection resulting from the humidification process. A secondary cause of air movement will result from local disturbances of the atmospheric air in the immediate vicinity of the display shelves, but this has been reduced to a minimum in the present invention by lowering the shelves below the opening in the cabinet 12 so that the several edges forming such opening, in effect, overlap the shelves.

It is well known that a sample of air which has a high humidity is lighter in weight than another sample of dry air, the temperatures and pressures being the same. In the present invention the pans 46, 48 and 50 extend the full length of the cabinet 12 and the air passages 52 and 54 are of equal length. Thus, the humid air which exists over the water 56 will rise by convection on opposite sides of each of shelves 32, 34 and 36 assuring humidification of the air thereover. A minimum of disturbance of such air is assured by virtue of the partitions 38, 40 and 42 as well as the extended edges forming the opening in the cabinet 12.

In many instances it will be desired to add salt to the evaporating pans to eliminate the production of plant or animal life. For this reason, it is desirable to make the pans from material such as a polyester resin reinforced with fiberglass which can be economically produced and will not be subject to corrosion.

It may also be desired to add other well known compounds to the water solution to regulate the relative humidity of the air above the water. In this manner the relative humidity between certain temperature limits can be closely regulated and by virtue of the construction and arrangement of the pans and shelves a uniform relative humidity for prescribed temperature limits will always be maintained.

The present invention is found to operate in a very simple and economical manner. It employs a trouble-

free, inexpensive humidifying unit which can closely approach the required operating conditions.

Having thus described my invention, I claim:

- An humidification unit comprising a display cabinet having a series of upwardly staggered shelves therein with the lowermost shelf at the front of the cabinet, vertical partitions disposed longitudinally between adjacent shelves in horizontal spaced relation thereto, said cabinet having an open top providing access to said shelves, said shelves being mounted inward of the opening so that the edges forming said opening will substantially prevent circulation of air over said shelves, open pan-type humidifiers mounted below each of said shelves in juxtaposition thereto so that each open pan will be in communication with the spaces adjacent the shelf with which such pan is associated, and separate alarms for indicating when water in each of said pans is below a prescribed limit.
- An humidification unit comprising a display cabinet having an opening through which merchandise displayed therein can be seen and selected by a purchaser, a series of shelves mounted adjacent to but inward from said opening on which such merchandise can be carried, said shelves being spaced apart laterally, vertical partitions carried between said shelves providing vertical air passages along the longitudinal edges of said shelves, open pan-type humidifiers mounted below each of said shelves in juxtaposition thereto so that each open pan will be in communication with said air passages adjacent the shelf with which such pan is associated, and separate alarms for indicating when water in each of said pans is below a prescribed limit.
- An humidification unit comprising a display cabinet having an opening through which merchandise displayed therein can be seen and selected by a purchaser, a series of shelves mounted adjacent to but inward from said opening on which such merchandise can be carried, said shelves being spaced apart laterally, vertical partitions carried between said shelves providing vertical air passages along the longitudinal edges of said shelves, and open pan-type humidifiers mounted below each of said shelves in juxtaposition thereto so that each open pan will be in communication with said air passages adjacent the shelf with which such pan is associated.
- An humidification unit comprising a display cabinet having an opening through which merchandise displayed therein can be seen and selected by a purchaser, a series of shelves mounted adjacent to but inward from said opening on which such merchandise can be carried, said shelves being spaced apart laterally, vertical partitions carried between said shelves providing vertical air passages along the longitudinal edges of said shelves, float controlled pan-type humidifiers mounted below each of said shelves in juxtaposition thereto so that each open pan will be in communication with said air passages adjacent the shelf with which such pan is associated, and separate alarms for indicating when water in each of said pans is below a prescribed limit, said alarms comprising mercury switches associated with float mechanisms of the pan-type humidifier and electric circuits including said switches and electric lamps so that when the water level in any pan drops below a prescribed level the mercury switch will tilt closing a circuit to energize one of said electric lamps.
